UNITED STATES PATENT OFFICE.

JOHN B. OLINGER, OF DENVER, COLORADO.

GENEALOGICAL RECORD.

1,098,833.

Specification of Letters Patent. Patented June 2, 1914.

Application filed April 1, 1912. Serial No. 687,846.

To all whom it may concern:

Be it known that I, JOHN B. OLINGER, citizen of the United States, residing in the city and county of Denver and State of Colorado, have invented certain new and useful Improvements in Genealogical Records; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in genealogical records, my object being to provide a book for this purpose, the leaves of which are so constructed and arranged that those containing data with reference to a considerable number of persons either in the ancestry or the posterity line, may be turned, while the leaf containing the name of the person whose ancestors, or the persons whose posterity is to be considered, has a portion exposed containing the name of such person or persons. For instance, referring first to the ancestry line, my improved book has a series of leaves, the longest of which is the full-sized leaf of the book and has the name of the person whose ancestry is considered, on the bottom portion of the leaf which is exposed, all the other leaves containing the ancestry record being shorter.

In the accompanying drawings I have illustrated my improved record to such extent as I have considered necessary, and in this drawing it must be understood that the leaves of the record heretofore outlined, which are not disclosed, are substantially a repetition of the leaves which are illustrated.

In this drawing: Figure 1 is a view of the record looking at the first leaf of the ancestral record of the father's side of the family, the lower portion of two other leaves of the record being disclosed. Fig. 2 is a view of the same with certain of the shortest leaves removed disclosing completely a leaf of medium length and the lower portion of one of the leaves of greatest length. Fig. 3 is a view of one of the longest leaves alone. Fig. 4 illustrates the record so far as it relates to posterity.

Throughout the drawings the edges of the various sheets are indicated by full lines,

while ruling lines, etc., upon the sheets, are indicated by broken lines.

Referring now to the drawing, it will be seen that the first leaf *a* disclosed in Fig. 1 is adapted to contain data concerning one grandfather and the corresponding great-grandfather and the great-grandmother of the person whose name is to be written on the lower part of the third sheet. The first leaf *a* is also adapted to contain data concerning relatives of the grandfather of the same generation, as great-uncles and great-aunts.

The portion of the leaf *b* which extends below the first leaf is adapted to contain the name of the father, of "self" or the name of the person whose name is to be written on the lower part of the third leaf. This leaf *b* (see Fig. 2) is also adapted to contain data concerning relatives of the father of the same generation, as uncles and aunts of "self," and also data with reference to relatives of the father of the second generation, as cousins of self.

Between the first leaf *a* and the leaf *b* illustrated in the drawing, there must be a second leaf *a* in the record of the same size as the first leaf *a*, and adapted to contain data concerning one grandmother of self, and the corresponding great-grandparents on the father's side, together with data concerning the grandmother's relatives of the same generation, as great-uncles and great-aunts of self. However, as this leaf containing data with reference to the grandmother is a repetition in every respect of the first leaf except that the word "grandmother" is used in place of the word "grandfather" on the line where the grandmother's name is to be written, it does not appear necessary to disclose this in detail in the drawing.

Between the first leaf *b* illustrated in the drawing, or the leaf adapted to contain the name of the father of self, on its extended portion, and the leaf *c* containing the name of self, there should be three leaves that is, one leaf *b* and two leaves *a* adapted to contain data with reference to the mother's side of the family, but as these leaves are a repetition of the leaves of the record adapted to contain data concerning the father's side of the family, it has not been considered necessary to illustrate them in the drawing.

Passing now to the leaf *c* of the ancestry record illustrated in the drawing, this leaf

(see Fig. 3) contains the name of self on its lower portion, while its upper portion or that normally concealed by the other leaves, is adapted to contain data concerning relatives of self of the same generation, as brothers and sisters, and relatives of self of a generation once removed, as nieces and nephews.

The foregoing may be designated or considered Part I of the ancestry record. Following this is a Part II of the ancestry record which is a repetition of Part I, it being understood, however, that the two selves in Part I and Part II respectively are of the opposite sex, being the husband and wife hereinafter referred to in the posterity record.

Referring now to Fig. 4 which is intended to illustrate the posterity record, this view discloses the first sheet *d* in full, a sheet *e* partially (the upper extremity thereof only being seen), and the upper portion only of the last sheet *f*. The sheet *f* is adapted to contain the names of the husband and wife whose posterity is to be recorded in the preceding sheets, being the two selves referred to in the ancestry record.

The sheets *d* of this posterity record are adapted to contain the names of the grandchildren and great-grandchildren of the said husband and wife, together with other data concerning these individuals.

The first sheet *e* extends above the sheets *d* and is adapted to contain the name of the eldest child of the husband and wife, together with other data concerning this child. The name of the child is to be written on a line which is designated by the numeral "1".

The names of the grandchildren and great-grandchildren appearing on the first leaf *d* are the children and the children's children of the eldest child, or of the one whose name appears on the first leaf *e*.

Between the leaf *f* illustrated in the drawing, or the last leaf of the posterity record, and the first leaf *e* of this record, is any desired number of pairs of leaves, each pair being a repetition of the first and second leaves of the posterity record, depending on the number of children of the husband and wife. For instance, the second pair of leaves are adapted to contain the name of the second child which is written on the second leaf of this pair, together with other data concerning the second child, while the first leaf of the second pair contains the names of the grandchildren and great-grandchildren of the husband and wife, being the children and the children's children of the second child; and so on, there being a pair of leaves devoted to each child of the husband and wife.

The last leaf *f*, in addition to the names of the husband and wife, is adapted to contain other data concerning these individuals,

which data may be written or printed on the portion of this last leaf which is normally concealed by the other leaves.

Attention is called to the fact that the leaves of the record are removable; the perforations *g* at the left of the sheets in the drawing are indicated to disclose this feature. Attention is also called to the fact that as the ancestry record has its short leaves shortened at the bottom while the posterity record has its short leaves shortened at the top, there is no opportunity for paging these leaves either at the top or at the bottom in the usual way. I therefore place the page numbers on the right-hand edge of the center approximately of the longest sheets, and the page numbers of the shorter leaves in a corresponding position, thus making it practicable to have the page numbers of all the leaves correspondingly and conveniently arranged for reference.

By virtue of the variation in the length of the various sets of leaves of the book, a complete line of direct ancestry or posterity for one or more individuals may be disclosed at a single view without turning any leaves, the direct ancestry or posterity line being continued to a predetermined generation.

Having thus described my invention, what I claim is:

1. A genealogical record book including three leaves varying in length, the first leaf being the shortest, the last leaf, the longest, the exposed portions of the under leaves being located upon the same side of the book, the normally exposed portion of the last leaf bearing indicia for the name of the person whose genealogy is contained in the record, the normally exposed portion of the leaf next above bearing indicia for the name of the person belonging to a generation once removed, the adjacent portion of the first leaf bearing indicia for data concerning a person belonging to the third generation, the remaining portion of each leaf bearing indicia for data concerning the brothers and sisters of the said respective persons, the indicia being such that the said persons are those in a direct line of descent, and the exposed indicia of each leaf serving as an index for that which is concealed.

2. A record of the class described, comprising a series of leaves, the first two leaves containing indicia for data with reference to the two grandparents and the corresponding four great-grandparents of self on the father's side, the third leaf extending below the first two leaves, its exposed portion containing indicia for data concerning the father, the normally concealed portion of this leaf containing indicia for data concerning the father's relatives of the same generation, the fourth and fifth leaves being of the same size as the first two leaves, and

containing indicia for data concerning the two grandparents and the corresponding four great-grandparents of self on the mother's side; the sixth leaf being of the same length as the third leaf, its portion which extends below the fourth and fifth leaves containing indicia for data concerning the mother of self, the portion of this leaf concealed by the fourth and fifth leaves containing indicia for data concerning relatives of the mother of the same generation; while the last leaf, which is the longest, has an exposed portion extending below all the other leaves and containing indicia for data concerning self, the normally concealed portion of this leaf containing indicia for data concerning relatives of self of the same generation.

3. A genealogical record book having a set of leaves of increasing length from the first to the last, each of said leaves bearing indicia for data concerning related persons of the same generation, the leaves being so positioned in the book that the different generations shall be arranged in regular order progressively from one end of the book to the other, the indicia being so arranged upon the leaves that normally indicia for data concerning a complete line of direct ancestry will be exposed.

4. A book having a set of leaves of unequal length, the first two leaves containing indicia for data concerning the grandparents and great-grandparents of self on one parent's side, the third leaf being longer, its exposed portion containing indicia for data concerning one parent, its concealed portion containing indicia for data concerning relatives of the said parent of the same generation; the fourth and fifth leaves being of the same size as the first two leaves and containing indicia for data concerning grandparents and great-grandparents of self on the other parent's side; the sixth leaf, which is of the same size as the third leaf, containing on its portion exposed when the

first three leaves are turned over, indicia for data concerning the other parent, the normally concealed portion of this leaf containing indicia for data concerning relatives of the last named parent of the same generation, the seventh leaf, which is the longest, containing on its exposed portion indicia for data concerning self, the normally concealed portion of this leaf containing indicia for data concerning the relatives of self of the same generation; a second set of leaves constituting a repetition of the first set of leaves and containing indicia for data concerning the ancestors of a second "self" of different sex from that of the self referred to in the first set of leaves; and a third set of leaves of different length following the first and second sets, the longest leaf having its top portion exposed and containing indicia for data concerning husband and wife, being the two selves heretofore mentioned; a number of shorter leaves immediately preceding the said longest leaf, the shorter leaves respectively containing indicia for data of children of the husband and wife, and the first and shortest leaf of the third set containing indicia for data concerning the grandchildren and great-grandchildren of the said husband and wife.

5. A genealogical record composed of a series of leaves superposed one upon another, each leaf after the first being slightly longer than the preceding leaf, indicia for data of one generation being placed on each leaf, and the leaves being consecutively arranged according to the generations, the exposed portions of the leaves bearing only indicia for the data of persons in a direct line of descent.

In testimony whereof I affix my signature in presence of two witnesses.

JOHN B. OLINGER.
